(57) **CLAIM**

The ornamental design for a wearable device, as shown and described.

DESCRIPTION

FIG. 1 is a bottom, front, and right perspective view of a first embodiment of the wearable device showing our new design.

FIG. 2 is a front view of the first embodiment of the wearable device of FIG. 1.

FIG. 3 is a back view of the first embodiment of the wearable device of FIG. 1.

FIG. 4 is a bottom view of the first embodiment of the wearable device of FIG. 1.

FIG. 5 is a top view of the first embodiment of the wearable device of FIG. 1.

FIG. 6 is a right side view of the first embodiment of the wearable device of FIG. 1.

FIG. 7 is a left side view of the first embodiment of the wearable device of FIG. 1.

FIG. 8 is a bottom, front, and right perspective view of a second embodiment of the wearable device showing our new design.

FIG. 9 is a front view of the second embodiment of the wearable device of FIG. 8.

FIG. 10 is a back view of the second embodiment of the wearable device of FIG. 8.

FIG. 11 is a right side view of the second embodiment of the wearable device of FIG. 8.

FIG. 12 is a left side view of the second embodiment of the wearable device of FIG. 8.

FIG. 13 is a bottom view of the second embodiment of the wearable device of FIG. 8.

FIG. 14 is a top view of the second embodiment of the wearable device of FIG. 8.

FIG. 15 is a bottom, front, and right perspective view of a third embodiment of the wearable device showing our new design.

(Continued)

FIG. 16 is a front view of the third embodiment of the wearable device of FIG. 15.

FIG. 17 is a back view of the third embodiment of the wearable device of FIG. 15.

FIG. 18 is a bottom view of the third embodiment of the wearable device of FIG. 15.

FIG. 19 is a top view of the third embodiment of the wearable device of FIG. 15.

FIG. 20 is a right side view of the third embodiment of the wearable device of FIG. 15; and,

FIG. 21 is a left side view of the third embodiment of the wearable device of FIG. 15.

The claimed design is shown in solid lines in the drawings. The broken lines shown on the back of the design in FIGS. 1-12 and 17-21 illustrate portions of the wearable device that form no part of the claimed design. The broken line showing of a band in FIGS. 8-14 illustrates environment and forms no part of the claimed design. The shade lines in the figures show contour and form no part of the claimed design. The surface treatment applied to the sides of the wearable device as shown in FIGS. 1-7 and 15-21 and forming part of the claimed design is flat and two-dimensional, with no three-dimensional characteristics.
